UNITED STATES PATENT OFFICE.

THOMAS L. MCKEEN, OF EASTON, PENNSYLVANIA.

RAILWAY-CAR BUFFER.

SPECIFICATION forming part of Letters Patent No. 729,787, dated June 2, 1903.

Application filed February 16, 1903. Serial No. 143,496. (No model.)

To all whom it may concern:

Be it known that I, THOMAS L. MCKEEN, a citizen of the United States, residing at Easton, in the county of Northampton, in the State of Pennsylvania, have invented new and useful Improvements in Railway - Car Buffers, of which the following is a specification.

This invention relates more particularly to a friction-buffer for railway-cars.

10 The object of the invention is to provide a buffer of great capacity to cushion and absorb severe shocks and which is of simple, strong, and compact construction.

In the accompanying drawings, consisting 15 of two sheets, Figure 1 is a plan view, partly in section, of one end of a car and platform-frame equipped with a friction-buffer embodying the invention. Fig. 2 is a fragmentary longitudinal section of the buffer, on an enlarged scale, in line 2 2, Fig. 1. Fig. 3 is a 20 fragmentary horizontal section of the buffer in line 3 3, Fig. 2. Fig. 4 is a transverse vertical section of the buffer in line 4 4, Fig. 3. Fig. 5 is a perspective view, on an enlarged 25 scale, of one of the friction-blocks. Fig. 6 is a fragmentary horizontal section showing a buffer of slightly-different construction.

Like letters of reference refer to like parts in the several figures.

30 Figs. 1 to 5 of the drawings show the improvements applied to a platform-buffer of the well-known "Gould" type; but it will be understood that the invention is not limited in its useful application to this particular style of buffer, but is applicable generally to 35 buffers for railway-cars. Referring particularly to said Figs. 1 to 5, A represents the car end sill, B the platform end sill, which is connected to the car end sill by longitudinal sills 40 or beams, and C a metal casting or structure which replaces the ordinary center or draft sills and also serves as a support or housing for the springs and other parts of the buffer. D represents the buffer head or plate, which 45 is carried at the front ends of a center stem d and side stems d', which project rearwardly through holes in the platform end sill and are provided, as usual, with center and side coil-springs. In the construction shown this support or housing is bolted or otherwise secured at its front and rear ends, respectively, to said platform and car end sills and is provided

with longitudinal side portions c and a rear wall c' and intermediate of its ends with a transverse wall or plate c''. E represent the outer and inner center coil-springs, which surround the reduced rear portion of the central stem and abut at their rear ends against the transverse wall of the support. The forward ends of the center springs are engaged 55 by the usual follower e', which is slidably supported on the reduced portion of the central stem in rear of a shoulder e'' thereon. The light inside coil of the center buffer-springs is longer than the outside coil and permits an 60 initial movement of the buffer-head before the heavy outside coil is brought into action. The central buffer-stem projects rearwardly through the transverse wall of the casting C and carries a wedge-block F, the rear end of 65 which tapers or is provided with converging friction-faces f. The wedge-block is preferably loosely connected with the central buffer-stem, so that in the initial movement of the buffer in coupling the wedge-block is not 70 moved or brought into action. As shown, the rear end of the central stem projects into a longitudinal hole f' in the wedge-block and is connected to the latter by a key f'', which 75 passes through an elongated slot f''' in the central stem. The inclined faces of the wedge-block engage between two oppositely-inclined friction-faces on the friction-blocks G, which are preferably provided, as shown in the drawings, with upright longitudinal 80 walls g, upright front walls g', and horizontal bottom plates g''. The friction-blocks are supported and capable of lateral movement on suitable portions of the support C, such as ledges h, which project inwardly from the 85 opposite side portions of the support, and a horizontal shoulder or flange h', which projects forwardly from the rear vertical wall of the support. The friction-blocks are held from forward movement and are guided in 90 their lateral movement by vertical walls or flanges h'', which project inwardly from the side portions of the support in front of the front walls of the friction-blocks. I represents spring-plates or flat springs, which are 95 arranged in two sets. One set of the spring-plates rests on the horizontal bottom of each friction-block and bears at its opposite ends upon shoulders i, projecting inwardly from 100

the opposite side portions of the support C. The spring-plates are preferably bowed inwardly, and the central portion of the inner spring-plate of each set bears against the upright longitudinal wall of the adjacent friction-block. In coupling the cars the central stem of the buffer is permitted an initial rearward movement in which the inner coil of the central coil-springs is compressed and affords the necessary resistance to the inward movement of the buffer. When the follower strikes the outer coil of the center coil-springs, the front end of the slot in the central buffer-stem engages the key connecting it with the wedge-block, and in the further movement of the buffer, due to severe shocks or collisions, the wedge-block is carried rearwardly by the central stem and its inclined friction-faces, working on the inclined faces of the friction-blocks, spread or force the latter apart laterally and place the spring-plates under tension. When the pressure on the buffer is relieved, the coil-springs, which have been compressed in the inward movement of the buffer, release the wedge-block and return it to its normal position.

In the construction just described the wedge-block is carried by the buffer-stem and the friction-blocks and spring-plates are held from longitudinal movement and are only movable laterally. Manifestly, however, the friction-blocks and spring-plates can be arranged to move rearwardly with the buffer and coöperate with a stationary wedge. Such construction is shown in Fig. 6 of the drawings and is as follows: J represents the support or housing for the springs and other parts of the buffer. The support in this instance is of a shape to enable its employment with a platform having wooden longitudinal center or draft sills between which the spring-box is located. The support is provided at its opposite vertical sides with inwardly-projecting shoulders or ribs j and with a bottom j', extending longitudinally of the support from one to the other of the shoulders j. The rear end of the central buffer-stem K projects rearwardly through the platform end sill and has its rear portion reduced. L represents an intermediate or central follower which is arranged in rear of the front vertical ribs j of the support to slide longitudinally on the bottom of the latter. The follower is preferably provided with a forwardly-extending tubular shank l, in which the rear end of the buffer-stem telescopes, and surrounding this hollow shank is a coiled spring l', which abuts at its rear end against the intermediate follower and at its forward end against a front follower l'', which is arranged to slide on the reduced rear end of the buffer-stem and to engage a shoulder l''' thereon, which limits the forward movement of the front follower. M represents a rear follower which is arranged to slide longitudinally on the bottom of the support in front of the rear vertical ribs j thereof. N is the wedge-

block, which is provided at its front end with oppositely-inclined or converging friction-faces. The wedge-block is provided with a rearwardly-projecting shank which extends through a hole in the rear follower and bears at its rear end against the rear end of the support which affords a stop or abutment for the wedge-block. n represents the coil-springs, which surround the shank of the wedge-block and bear at their rear ends against the rear wall of the support and at their front ends against the rear face of the rear follower. The rear end wall of the spring-box is preferably provided with a circular socket or seat n' for the reception of the rear ends of the coil-springs. O represents the oppositely-arranged friction-blocks, which are provided with vertical inclined friction-faces o, engaging the inclined friction-faces of the wedge-block. The friction-blocks are movable on the bottom of the support C and abut at their ends against the intermediate and rear followers. P represents the two sets of spring-plates or flat springs, one set of which is arranged between each of the friction-blocks and the adjacent side wall of the support, between the intermediate and rear followers. The central portion of the inner spring-plate of each set bears against the adjacent friction-block. q represents wear or friction plates which are preferably employed and are arranged to bear against the side walls of the support between the intermediate and rear followers. The front coil-spring, which surrounds the hollow shank of the intermediate follower, is comparatively light and permits the initial movement of the buffer in coupling the cars. When the buffer is moved rearwardly sufficiently far for the front follower to engage the front end of the hollow shank of the intermediate follower, the latter, together with the friction-blocks, spring-plates, wear-plates, and rear follower, are moved rearwardly against the action of the rear coil-springs. As the friction-blocks move rearwardly they are spread apart or moved laterally outward by the stationary wedge-block and compress or strain the spring-plates or flat springs which resist the lateral movement of the friction-blocks. The pressure due to the combined friction and action of the spring-plates gives the buffer great capacity to resist severe shocks incident to unduly forcing the cars together in coupling up the locomotive, sudden applications of the brakes, or other causes. The capacity of the friction-blocks and spring-plates to resist the inward movement of the buffer is much greater than can be secured by the employment of coiled springs, owing to the restricted space allowed for the buffer-springs in the usual car constructions.

I claim as my invention—

1. The combination of a stationary spring-support, a buffer-head provided with a stem projecting into said spring-support, a coil-spring acting against said stem, a wedge-block, friction-blocks movable laterally on

said support and having inclined faces bearing against the inclined faces of said wedge, and spring-plates which press said friction-blocks against said wedge and act to resist the lateral movement of said friction-blocks, substantially as set forth.

2. The combination of a buffer-head provided with a stem, a coil-spring surrounding said stem and acting to resist the inward movement of said stem, inclined faces movable with said stem and bearing against opposing inclined faces, two of said inclined faces being carried by laterally-movable blocks, and spring-plates which act to resist the lateral movement of said blocks, substantially as set forth.

3. The combination of a buffer-head provided with a stem, a spring-support, a coil-spring arranged between a part carried by said support and a part carried by said stem, a wedge adapted to be moved by said stem, friction-blocks which are movable laterally on said support and provided with friction-faces engaging the inclined faces of said wedge, and spring-plates arranged between said friction-blocks and the sides of said sup-

port and which act to resist the lateral movement of said friction-blocks, substantially as set forth.

4. The combination of a buffer-head provided with a stem, a spring-support provided with a stationary transverse wall, a coil-spring surrounding said stem between a part carried by the stem and said transverse wall, friction-blocks which are held from longitudinal movement but capable of lateral movement on said support, a wedge loosely connected to said stem whereby the latter is permitted an initial movement independently of the wedge, said wedge having inclined faces engaging friction-faces on said friction-blocks, and spring-plates arranged between said friction-blocks and the sides of said support and acting to resist the lateral movement of said friction-blocks, substantially as set forth.

Witness my hand this 13th day of February, 1903.

THOMAS L. MCKEEN.
